US0D1082796S

(12) **United States Design Patent** (10) **Patent No.:** **US D1,082,796 S**
(45) **Date of Patent:** **** Jul. 8, 2025**

(54) **SCREEN PROTECTOR**

(71) Applicant: **Fuyun Wang**, Yiyang (CN)

(72) Inventor: **Fuyun Wang**, Yiyang (CN)

(**) Term: **15 Years**

(21) Appl. No.: **29/972,232**

(22) Filed: **Nov. 8, 2024**

(30) **Foreign Application Priority Data**

Jul. 10, 2024 (CN) 202430428908.7

(51) **LOC (15) Cl.** **14-03**

(52) **U.S. Cl.**

USPC **D14/440**

(57) **CLAIM**

The ornamental design for a screen protector, as shown and described.

DESCRIPTION

FIG. 1 is a front perspective view of a screen protector, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 2.

The dash-dot-dash broken lines encircling the enlarged views are for annotative purposes only and form no part of the claim thereof.

1 Claim, 9 Drawing Sheets
